CABINET IRONING BOARD

Lenzo B. Wiley, Huntington, W. Va.

Application June 12, 1941, Serial No. 397,813

1 Claim. (Cl. 38—105)

This invention relates to a novel construction of kitchen cabinet, and particularly to a utility cabinet provided with an ironing board which is attached to the cabinet and which may be readily moved from a concealed, retracted position within the cabinet, to a projected, operative position, projecting outwardly from the cabinet.

More particularly, it is an aim of the invention to provide a cabinet having a recess for receiving an ironing board and means for connecting the ironing board to the cabinet to permit the ironing board to slide and swing relatively to the cabinet for moving it to or from a projected or retracted position relatively to the cabinet.

Still another aim of the invention is to provide a supporting brace for the ironing board, when in a projected position, which is adjustably attached to the cabinet and supported thereby, when in an operative position for supporting the ironing board, and which will likewise be supported in a channel or groove in the side of the cabinet when the ironing board is in a retracted position.

Still a further aim of the invention is to provide a kitchen cabinet having a table top beneath which the ironing board is disposed, when contained in the cabinet, and having means for detachably mounting removable cabinet sections on the ends of the cabinet, which removable cabinet sections extend from the top to the bottom of the cabinet.

Other objects and advantages of the invention will hereinafter become more fully apparent from the following description of the drawings, which illustrate a preferred embodiment of the invention, and wherein:

Figure 1 is a front elevational view of the cabinet in its entirety.

Figure 2 is an enlarged horizontal sectional view taken substantially along the plane of the line 2—2 of Figure 1.

Figure 3 is an enlarged fragmentary vertical sectional view taken substantially along the plane of the line 3—3 of Figure 1, and showing the ironing board in section and in an extended position, and

Figure 4 is a fragmentary cross sectional view, taken substantially along the plane of the line 4—4 of Figure 2, of a portion of the cabinet, and showing the ironing board in a retracted position.

Referring more particularly to the drawings, wherein like reference characters designate like or corresponding parts throughout the different views, 10 designates generally the cabinet in its

entirety, and which includes a main cabinet body, designated generally 11, having an upper cabinet portion, designated generally 12, and a lower cabinet portion, designated generally 13.

As best seen in Figure 3, the lower portion 13 of the cabinet body 11 projects outwardly substantially beyond the upper portion 12. A table top 39 is disposed between the cabinet portions 12 and 13 and extends outwardly beyond the front portion of the cabinet portion 13. Directly beneath the table top 39, the cabinet portion 13 is provided with a horizontally disposed recess or space 45 which extends substantially the length thereof, and the purpose of which will hereinafter be described.

Referring particularly to Figures 2, 3 and 4, the recess 45 is formed in the outer portion of the lower cabinet section 13 and extends substantially from end to end thereof, and opens outwardly of its front. The open side of recess 45 is restricted by a rail 58 which extends from end to end of the recess 45 and which rises above the bottom of recess 45 so that its open side has a restricted slot-like opening 59 at the top thereof. Opening 59 is of a size to receive an ironing board 61.

The ironing board 61 is provided with a straight longitudinal edge 62 and an enlarged end 63 and a restricted end 64. The enlarged end 63 is provided with a longitudinal slot 65, which is disposed adjacent to the longitudinal edge 62 and which is adapted to loosely engage a screw or stud 66, as best seen in Figure 3, which extends through the table top 39 and into the rail 58, intermediate of its ends. The length of the ironing board 61 is slightly less than that of the recess 45 in which it is adapted to be disposed when not in use, as illustrated in Figures 2 and 4. The underside of the ironing board 61 is provided with a transversely disposed abutment member 67 which is secured to its end 63, and which terminates in spaced relationship to the edge 62. A handle 68, having a recessed inner side, as seen in dotted lines in Figure 2, is attached to the edge 62, adjacent the end 64 of the ironing board 61 and extends downwardly therefrom for providing a handle for swinging the ironing board 61 from a retracted position in the recess 45 to a projected position, projecting outwardly therefrom, as seen in dotted lines in Figure 2, and in full lines in Figure 3. A stop 69 is secured in an end of the recess 45, to provide an abutment for the end 64 to limit the inward movement of this end of the ironing board as the ironing board is moved to a retracted position.

From the foregoing it will be obvious that the ironing board can be moved from its position, as seen in Figure 2, to its position, as seen in Figure 3, by grasping the handle 68 to swing the end 64 outwardly sufficiently so that it will be out of the recess 45 after which the ironing board can be slid away from the cabinet portion 13 due to the slot and stud connection 65 and 66, respectively, until the abutment member 67 engages the inner side of the rail 58 to cause the ironing board to swing to a position at right angles to the rail 58 so that the abutment member 67 will be engaging flush thereagainst and so that the ironing board 61 will be in a position, as seen in Figure 3, ready for use. The ironing board can be returned to an inoperative position in the recess 45 by swinging its outer end 64 back toward the stop 69 and then sliding the ironing board 61 inwardly of the recess 45 until its end 64 can be moved into the recess. When the end 64 is in engagement with the stop 69 the outer longitudinal edge 62 of the ironing board will be substantially parallel to the outer side of the rail 58.

Below recess 45 is a space 70. The space 70, adjacent its outer end, is provided with an upwardly extending wall strip 71 which terminates below the top thereof to form an opening 72 thereabove and which is offset inwardly from the front of the cabinet portion 13 to provide a channel or groove 73. The strip 71 is provided with a notch 74 in its outer side and at its upper end. A brace member 75 is adapted to be seated in the groove or channel 73 and is provided adjacent its upper end with a screw eye 16 which projects into the opening 72 and to which is connected one end of a contractile coil spring 77, the opposite end of which is secured to an anchor member 18 which is secured in the space 70 of the cabinet section 13, intermediate of the front and back thereof. As seen in dotted lines in Figure 3, the contractile spring 77 functions to hold the brace 75 in its dotted line position in the channel 73, when it is not in use and when the ironing board 61 is in a retracted position in the recess 45. The ironing board 61 is provided with a notch 79 in its underside, intermediate of its ends, and the upper end 80 of the brace 75 is beveled to fit the notch 79. The lower end 81 of the brace 75 is likewise beveled to fit flush into the notch 74 when the end 80 is seated in the notch 79 so that the brace 75 will be disposed diagonally to the plane of the ironing board 61 and to the plane of the front of the cabinet section 13, as illustrated in Figure 3. In this position, the spring 77 will hold the ends 80 and 81 in engagement with the notches 79 and

74, respectively. The notch 79 and the end 80 are so shaped that the brace 75 can be swung from its operative position, as seen in Figure 3, downwardly to cause its end 80 to move out of engagement with the notch 79 so that its end 81 can be released from the notch 74 to permit the brace 75 to be moved to its dotted lines position, and as the spring 77 will create an upward pull on the upper end of the brace 75 in its operative position, it will be readily apparent that said spring will hold the end 80 in engagement with the notch 79. A fingerhold 82, as best seen in Figure 3, which is recessed on its under and inner sides, is attached to the outer side of the brace 75, adjacent its upper end, to provide means for withdrawing the brace from the channel 73 for moving the brace from its inoperative to its operative position.

Various modifications and changes are contemplated and may obviously be resorted to as only a preferred embodiment of the invention has been disclosed.

I claim as my invention:

A cabinet provided with a horizontally disposed longitudinally extending recess, said recess opening outwardly of one side of the cabinet, an ironing board disposed in said recess of approximately the same length as the recess with one end of the board cut away on a line extending inwardly and toward the opposite end of the board, means for pivotally and slidably connecting the ironing board to the recess to permit said ironing board to slide and swing relatively to the cabinet for moving the ironing board into or out of the recess, said cabinet being provided with a vertical groove in its outer side, and an opening communicating with the upper portion of said groove and opening into the interior of said cabinet, said cabinet being provided with a socket opening into the groove, below said opening, a brace disposed in said groove, a contractile coil spring attached to said brace, adjacent its upper end, at one end thereof, and attached to the interior of the cabinet at its opposite end, said spring extending through said opening for holding the brace in a retracted position in the groove, a notch in the underside of said ironing board, intermediate of its ends, the upper end of said brace being beveled to engage said notch, when the brace is in an extended position, diagonally to the cabinet and ironing board, and the lower end of said brace being beveled to engage said socket, when the brace is in an extended position, said contractile coil spring supporting said brace in an extended or retracted position.

LONZO B. WILEY.
